UNITED STATES PATENT OFFICE

ARTHUR H. BELL, OF DENVER, COLORADO.

BROODER.

1,020,252.

Specification of Letters Patent. Patented Mar. 12, 1912.

Application filed April 26, 1911. Serial No. 623,354.

To all whom it may concern:

Be it known that I, ARTHUR H. BELL, a citizen of the United States, residing at Denver, in the county of Denver and State 5 of Colorado, have invented certain new and useful Improvements in Brooders, of which the following is a specification.

My invention relates to an improvement in brooders, and the object is to provide 10 means for supporting a heating receptacle within the brooder, and a further object is the provision of means for protecting the chicks from coming in contact with the heating medium.

15 The invention consists in certain novel features of construction and combinations of parts which will be hereinafter fully described and pointed out in the claims.

In the accompanying drawings, Figure 1 20 is a perspective view of the brooder; Fig. 2 is a vertical sectional view; Fig. 3 is a plan view of the disk or collar; and Fig. 4 is a detail sectional view, showing the manner of supporting the screen upon the disk or 25 collar.

A, represents the brooder, which is provided with a runway 1 at one end. A door 2 is connected to the brooder, whereby the chicks can pass from the brooder into the 30 runway. A curtain 3 is mounted upon a roller 4, which is supported upon the frame of the runway 1, whereby the top of the runway 1 can be closed when desired. A collar or disk 5 is received within the 35 brooder, and is provided with an outer annular flange 6, which is provided with slots or perforations 7 at predetermined intervals through which the bars 8 extend. A hook 9 is formed at one end of each bar, which 40 engages the disk or collar, and the other ends of the bars are provided with right angular hooks 10, which are inserted in the staples 11, secured to the body of the brooder A. Supported by the disk is a can or receptacle 12, in which the heating medium is 45 received. It is my intention to use ashes as a heating medium, as they supply a very even temperature for a period varying with weather conditions from twelve hours in extreme cold weather to forty-eight hours and even longer in mild winter weather. The 50 ashes are removed from the receptacle and a fresh supply inserted at various intervals for retaining the proper temperature in the brooder. An annular screen 13 surrounds

the receptacle 12 and is provided with openings through which the bars 8 extend. The screen is provided with rims 14 at each end, and the screen is supported by the disk by means of hooks 14' one end of the hooks 60 engaging the flanges 6 of the collar and the other end passing beneath the lower rim 14 of the screen. The lower rim of the screen has a brooder cloth 15 sewed thereto, which extends downward toward the bottom of the 65 brooder for retaining the heat beneath the heating receptacle. The receptacle 12 is provided with a cover 16.

The temperature of the ashes which are deposited within the receptacle 12 can be 70 governed or regulated so that the brooder can be heated to a desired temperature, and in extreme cold weather, hot coals can be introduced into the receptacle for obtaining a greater or excessive heat within the 75 brooder than under ordinary conditions. When hot coals are placed within the receptacle, they are generally smothered between layers of loose or dead ashes.

It will be noted that I have provided a 80 simple device which consists of few parts which can be assembled and disconnected readily. The wire screen 13 forms a medium for preventing the chicks from coming in contact with the heating receptacle 12, 85 and the heating receptacle is supported within the brooder at an elevation sufficiently high so that the chicks can pass beneath the heating receptacle.

Having fully described my invention, 90 what I claim as new and desire to secure by Letters Patent, is:—

1. The combination with a brooder, of a disk, bars removably connected to the disk for supporting the disk at an elevation within the brooder, a heating medium supported upon the disk, a screen surrounding the heating medium, and means connected to the disk for supporting the screen. 95

2. The combination with a brooder, of a disk, bars for supporting the disk, a screen, means for supporting the screen upon the disk, a brooder cloth connected to the screen, and a heating receptacle supported by the disk. 100

3. The combination with a brooder, a disk having an upturned flange at its outer edge, this flange slotted, bars secured to the disk and extending through the slots in the flange, the bars having hooks on their outer 110

ends, and staples on the wall of the brooder to receive the hooks, of a can or receptacle supported on the disk to receive the heating element, an annular screen surrounding the 5 flange on the disk, a brooder cloth or curtain depending from the lower edge of the screen, and a cover for the can or receptacle.

In testimony whereof I affix my signature, in the presence of two witnesses.

ARTHUR H. BELL.
